(57) **CLAIM**

The ornamental design for a front bumper for a automobile, as shown and described.

DESCRIPTION

FIG. 1 is a front elevational view of a front bumper for an automobile showing our new design;

FIG. 2 is a top plan view thereof;

FIG. 3 is a bottom plan view thereof;

FIG. 4 is a right side elevational view thereof;

FIG. 5 is a left side elevational thereof;

FIG. 6 is a top, front and right side perspective view thereof; and,

FIG. 7 is a bottom, front and left side perspective view thereof.

The rear view of the front bumper forms no part of the claimed design. The inside surfaces of the front bumper form no part of the claimed design. The front bumper is configured to be mounted to an automobile. The inside surfaces of the front bumper, visible in FIGS. 2, 3, 6, and 7, form no part of the claimed design since the inside surfaces are hidden when the front bumper is mounted to the automobile. Further, the surfaces for mounting a radiator grille, visible in FIG. 2, form no part of the claimed design since the mounting surfaces are hidden when the radiator grill is mounted to the front bumper.
